UNITED STATES PATENT OFFICE

ROY KLOMPARENS, OF PROVIDENCE, RHODE ISLAND

DESIGN FOR A FURNACE REGISTER

Application filed July 20, 1931. Serial No. 40,604. Term of patent 14 years.

To all whom it may concern:

Be it known that I, ROY KLOMPARENS, a citizen of the United States, residing at the city of Providence, in the county of Providence and State of Rhode Island, have invented a new, original, and ornamental Design for a Furnace Register, of which the following is a specification, reference being had to the accompanying drawing, forming a part thereof.

The figure is a front perspective view of a furnace register showing my new design.

I claim:

The ornamental design for a furnace register, as shown.

ROY KLOMPARENS.
